FABRIC TAKE-UP DEVICE ON STRAIGHT-BAR KNITTING MACHINES

Hans Diem, Neuchatel, Switzerland, assignor to
Edouard Dubied & Cie. (Societe Anonyme)
Neuchatel, Switzerland

Application September 13, 1949, Serial No. 115,545
In Switzerland October 9, 1948

7 Claims. (Cl. 66—152)

1

My present invention relates to improvements in fabric take-up devices on straight-bar knitting machines having automatically reciprocated draw-off hooks for the manufacture of hosiery of all kinds, i. e. also of knitted ware ready for use such as ware involving baggy enlargements.

In accordance with my present invention, the said hooks operate in reciprocal action with an automatically controlled clamping device which receives the hosiery and holds the same when the draw-off hooks move upwardly on idling strokes, but releases the hosiery when the said hooks move downwardly on their working strokes.

Such alternate operation of draw-off hooks and clamping device permits to attain, by comparatively simple means, a positive uniformly intermittent take-up or draw-off of the hosiery while carefully handling the loops, irrespective of whether the hosiery produced be of constant or varying width.

One form of my invention is illustrated in the accompanying drawing, in which—

Fig. 1 shows the fabric take-up device on a pearl flat-knitting machine, in a vertical cross-section on the line I—I of Fig. 3, the draw-off hooks being in the operative position.

Fig. 2 is a vertical cross-section on the line II—II of Fig. 3, the clamping device being in the operative position, and

Fig. 3 is an elevation seen in direction of the arrow A in Fig. 1, the front needle bed together with the frame, however, being partly omitted.

The numeral 1 designates the needle-bed frame of the knitting machine, 2 and 3 the front and the rear needle beds respectively, 4 the knitting needles, 5 the knitted ware, 6 and 6' two side walls provided on the frame 1, the entire take-up device being mounted intermediate of the said side walls. Elongated slide elements 8 are vertically guided by means of two horizontal angle irons 7 and 7'. A draw-off member 9 each is pivoted to the head ends of the elements 8, and terminates on top in three hooks which are parallel to each other. The foot ends of the draw-off members 9 are biased by a compression spring 10 each, and each slide element 8 by a compression spring 11 mounted thereon. The tension of each spring 11 may be adjusted by means of a pin 12 which for such purpose may be plugged alternatively in any one of a plurality of notches 13 of a longitudinal slot provided on the elements 8. Each said spring 10 is inserted in a horizontal bore provided in the thickened head portion of the elements 8.

2

A control bar 14 connected to the machine drive is associated with all the slide elements 8.

In the upper portion of said frame 1 an angle iron 15 is provided, to which a horizontal stop strip 16 for the knitted ware 5 is secured. The said strip at the same time constitutes the fixed part of the clamping device. A digitated strip 17 permits the draw-off members 9 to pass therethrough for the purpose of guiding the same and, therefore, also the draw-off hooks. The latter are directly guided by means of a horizontal abutment strip 18 of which the head has the form of a comb, which strip constitutes the movable part of the clamping device. The abutment strip 18 by virtue of its form and shape at the same time serves for guiding the knitted ware 5, and is rotatably mounted on a shaft 20 by means of arms 19 of which one only is shown in Fig. 3. The said strip 18 is biased by tension springs 22 which are secured to holders 23 of which one only is shown in Fig. 3. The holders 23 bear against the two angle irons 7 and 7', being adjustable in position relative to the angle iron 7' by means of a set screw 24 each for the purpose of adjusting the tension of the springs 22. The latter serve for holding the strip 18 against the thumb pieces 26 which are secured to the shaft 20. A two-arm control lever 25 is pinned to the shaft 20, one arm of which is biased by a spring 21, and to the other arm of which a link 27 is pivoted. The latter establishes the connection to the machine drive.

When the knitting machine is in operation, the control bar 14 is periodically moved up and down from the machine drive, and the shaft 20 is rocked to and fro through the link 27 and the control lever 25. The spring-loaded slide elements 8 follow the movements of the bar 14. When the elements 8 move upwardly, the draw-off members 9, which are carried by the elements 8, slide with their hooks over the knitted ware 5 which, as shown in Fig. 2, is held in the clamping device 16 and 18, the said hooks being laterally guided between the prongs or tines of the abutment strip 18 and the fingers of the strip 17. By virtue of such guiding arrangement, the draw-off hooks move in exactly parallel relation to the looper rods of the clamped knitted ware 5 of which the loops thus are carefully handled. After the slide elements 8 have attained their upper terminal position, the hooks of the rockable draw-off members 9, being biased by the springs 10, mesh with the loops of the ware 5. When the clamping device 18 and 16 is tripped, the said hooks, sliding along the stop

strip 16, pull the ware 5 downwardly on the downward run of the slide elements 8. The clamping device 16, 18 is tripped through the thumbs 26 secured to the shaft 20. When the shaft 20 is rocked in direction of the arrow B in Fig. 2, the thumbs 26 swing the abutment strip 18 against the action of the springs 22 about the shaft 20 into the position shown in Fig. 1. After the draw-off members 9 have performed their working stroke, the strip 18 through the springs 22 is swung in a direction opposite to the arrow B (Fig. 2) in accordance with the return movement of the thumbs 26, thereby closing the clamping device and again gripping the ware 5.

The draw-off hooks and the clamping device thus are alternately operated at a rate set by the machine drive. The fabric 5 is taken up or drawn off always across its entire width, irrespective of whether uniform or non-uniform amounts of fabric are produced.

Although the fabric take-up device represents a preferred embodiment of my present invention, it also, of course, may be constructed differently in its details. If desired, closed slots may be provided on the abutment strip 18, instead of interdental gaps or slots open at one end only, for the purpose of guiding the draw-off hooks. The strip 17, which provides a second guide means for the draw-off members 9, could be formed similarly as the modified strip 18. Further, individual spring-loaded draw-off hooks could be provided in place of draw-off members provided with a plurality of draw-off hooks.

What I claim as new and desire to secure by Letters Patent is:

1. In a straight-bar knitting machine for the production of knitted material, a take-up device extending over the working length of said machine comprising take-up hooks, automatic means for periodically moving said hooks up and down, a retaining device, automatic means controlling said retaining device and operating the same in synchronism with said take-up hooks in order to retain the material during the upward or no-load stroke of said take-up hooks.

2. A construction as set forth in claim 1 wherein said retaining device comprises a fixed stop part and a movable retaining part having guide slots therein for receiving said take-up hooks.

3. A construction as set forth in claim 2 wherein guide means are provided for said take-up hooks to guide them laterally towards a second point of said movable retaining part.

4. A construction as set forth in claim 1 wherein said retaining device comprises a fixed stop part and a movable retaining part having guide slots therein for receiving said take-up hooks, said movable retaining part having a guide surface for the knitted material and adjustable spring means acting upon said movable retaining part urging it in the direction of action.

5. A construction as set forth in claim 1 wherein double spring stress means are provided acting upon said take-up hooks, one of said means being operative in the lifting direction and the other in the engagement direction of the take-up hooks.

6. A construction as set forth in claim 5 wherein sliding elements are provided upon which said take-up hooks are oscillatably mounted, spring means for urging said sliding elements in the lifting direction and automatic control means for said sliding elements.

7. A construction as set forth in claim 6 wherein a plurality of take-up hooks are oscillatably mounted upon a single sliding element.

HANS DIEM.
